DESIGN FOR A HUMIDIFIER

Edward H. Horst, Clinton, Iowa, assignor to Patent Novelty Company, Fulton, Ill., a corporation of Illinois

Application October 13, 1937, Serial No. 72,142

Term of patent 7 years

To whom it may concern:

Be it known that I, Edward H. Horst, a citizen of the United States and resident of Clinton, in the county of Clinton and State of Iowa, have invented a new, original, and ornamental Design for a Humidifier, of which the following is a specification, reference being had to the accompanying drawing, forming a part thereof.

Fig. 1 is a front perspective of the humidifier, showing my new design.

Fig. 2 is a front elevation of said device.

Fig. 3 is an end view of said device.

I claim:

The ornamental design for a humidifier, as shown.

EDWARD H. HORST.
